DESIGN FOR A STERILIZING DEVICE

Frank J. Chandler and James B. Paton,
Detroit, Mich.

Application June 23, 1944, Serial No. 114,156

Term of patent 7 years

(Cl. D83—1)

To all whom it may concern:

Be it known that we, Frank J. Chandler and James B. Paton, citizens of the United States and residents of Detroit, Wayne County, Michigan, have invented a new, original, and ornamental Design for a Sterilizing Device, of which the following is a specification, reference being had to the accompanying drawing forming a part thereof.

In the drawing:

Figure 1 is a front perspective view of a sterilizing device showing our new design; and

Figure 2 is a side elevation of the sterilizing device.

It will be understood that the other side of the sterilizing device, not shown, is substantially the same as the side shown, and the back is substantially plain.

We claim:

The ornamental design for a sterilizing device, as shown and described.

FRANK J. CHANDLER.
JAMES B. PATON.
